CLAIM

The ornamental design for a smoking pipe, or similar article, as shown and described.

DESCRIPTION

FIG. 1 is a right side elevational view of a smoking pipe or similar article showing my new design, the left side being a mirror image thereof and the mouthpiece being conventional;

FIG. 2 is a top plan view thereof;

FIG. 3 is a front elevational view of the bowl and neck.

Fig.1.

Fig.2.

Fig.3.
